DESIGN FOR A BOOK-END

Ralph L. MacDonald, Niagara Falls, N. Y.

Application March 20, 1946, Serial No. 127,692

Term of patent 14 years

(Cl. D33—1)

To all whom it may concern:

Be it known that I, Ralph L. MacDonald, a citizen of the United States of America, residing at Niagara Falls, in the county of Niagara and State of New York, have invented a new, original, and ornamental Design for a Book-End, of which the following is a specification, reference being had to the accompanying drawing, forming part thereof.

The figure is a perspective view of a book-end, showing my new design.

I claim:

The ornamental design for a book-end, as shown.

RALPH L. MACDONALD.
